APPARATUS FOR CONTROLLING RAILWAY SWITCHES

John W. Logan, Jr., Forest Hills, Pa., assignor to
The Union Switch & Signal Company, Swiss-
vale, Pa., a corporation of Pennsylvania

Application March 13, 1940, Serial No. 323,764

12 Claims. (Cl. 246—219)

My invention relates to apparatus for controlling railway switches, and particularly to apparatus for normally controlling a switch from a remote point, but for at times modifying such control to permit operation of the switch from a point adjacent the switch.

Apparatus embodying my invention is particularly suitable for, although in no way limited to, use for controlling direct acting switch movements which are utilized in car retarder yards for diverting cars from the hump into the desired classification tracks. In yards of the type referred to, it has heretofore usually been customary to control all of the switches by means of switch levers located on a central control panel disposed in a tower. With this arrangement, if the humping crew only works a part of the time, for example one or two shifts, there are periods during the off-shift while the trains are being dispatched when it is desired to reverse the switches, and in order to effect this reversal it becomes necessary for a member of the train crew to ascend the tower and operate the proper switch lever since no towerman is then on duty. This occasions an undesirable delay, and the principal object of my present invention is to provide local control means at the individual switches for reversing the switches by power when the towerman is off duty to thereby eliminate these undesirable delays.

A further object of my invention is to arrange the auxiliary control means in a manner to maintain the correct functions of the indication circuits (carried over the same wires as the remote control circuits) while the switch is being controlled locally.

A still further object of my invention resides in the provision of means for automatically restoring a switch which has been reversed by operation of the local control means to a position in agreement with that of the remote control means after the train for which the switch was reversed has passed over the switch.

I accomplish the aforementioned objects by providing a local lever on the equipment adjacent to the switch, and by modifying the usual control circuits to permit control of the switch by the local lever and at the same time maintain the desired control of the indication circuits.

I shall describe three forms of apparatus embodying my invention, and shall then point out the novel features thereof in claims.

In the accompanying drawings, Fig. 1 is a diagrammatic view showing one form of apparatus embodying my invention. Figs. 2 and 3 are

fragmentary views showing mechanical details of a portion of the apparatus illustrated diagrammatically in Fig. 1. Figs. 4 and 5 are diagrammatic views similar to Fig. 1 showing other forms of apparatus embodying my invention.

Similar reference characters refer to similar parts in each of the several views.

Referring first to Fig. 1, the reference characters 1 and 1a designate the track rails of a stretch A of railway track, the one rail 1 of which is divided by means of insulated joints 2 to form a track section B—C. This track section is provided with a track circuit comprising a track relay D connected across the rails adjacent one end of the section, and a suitable source of track circuit current here shown as a battery 3, connected across the rails adjacent the other end of the section.

Located in section B—C is a switch E which connects the stretch A with a stretch of track J. The switch E is operated by suitable switch operating mechanism here shown as a motor M comprising a cylinder 4 containing a piston 5 operatively connected with the switch. Fluid under pressure, usually compressed air, is at times supplied to one end or the other of cylinder M from a suitable source, not shown in the drawings, and the supply of such fluid is controlled by a switch valve designated in general by the reference character V. The valve V comprises a normal magnet N and a reverse magnet R.

As shown in the drawings, the switch occupies its normal position. If, now, reverse magnet R is energized, fluid pressure will be supplied to motor M to operate switch 3 to its reverse position. If, when the switch occupies its reverse position magnet N is energized, valve V will supply fluid pressure to motor M to restore switch 3 to its normal position.

Operatively connected with the switch E is a circuit controller G comprising two contacts 6—6a and 7—7a which are closed when and only when the switch occupies its normal position, and two other contacts 6—6b and 7—7b which are closed when and only when the switch occupies its reverse position.

The magnets N and R of a switch valve V are controlled by the circuit controller G, by the track relay D, by a manually operable lever L, and by an auxiliary manually operable lever L1.

The lever L will usually be one of a number of similar levers located in a control cabin at a point remote from the switch, and as here shown is capable of assuming a normal position *n* and a reverse position *r*. Operatively connected with

the lever L are two contact arms 8 and 9. When the lever occupies its normal position in which it is shown in the drawings, the contact arm 8 engages a fixed contact member 8n to close a normal contact 8-8n and the contact arm 9 engages a fixed contact member 9n to close a normal contact 9-9n, whereas when the lever occupies its reverse position, the arm 8 then engages a fixed contact member 8r to close a reverse contact 8-8r and the arm 9 engages a fixed contact member 9r to close the reverse contact 9-9r.

The auxiliary manually operable lever L1 will usually be located adjacent to the switch, and may for example be similar to that described and claimed in Letters Patent of the United States No. 1,887,273, granted to Lloyd V. Lewis on November 8, 1932, for Circuit controllers. This lever has a normal position n and a reverse position r and operates two contact arms 10 and 11 which cooperate respectively with fixed contact members 10n and 11n to close normal contacts 10-10n and 11-11n, and with fixed contact members 10r and 11r to close reverse contacts 10-10r and 11-11r, according as the lever L1 occupies its normal or its reverse position.

Under some conditions it is desirable to prevent access to the lever L1 except by authorized persons, and to insure that the lever will be restored to its normal position after it is operated. When this is the case, the lever may be disposed inside the cover 12 for the switch operating mechanism in the manner shown in Figs. 2 and 3.

Referring to Figs. 2 and 3, as here shown the cover 12 is provided with a hinged door 13 which closes an opening 14, and the lever L1 is mounted inside of the cover on a suitable support 15 in such a position that when the door is open access to the lever may be had through the opening 14. The door 13 is provided with a hasp 16 which, when the door is closed, receives a staple 16a, and with a lug 17 which will engage the lever and prevent the door from being moved to its closed position unless the lever occupies its normal position in which it is shown in the drawing. When the hasp 16 is in place on the staple 16a, a padlock 18 may be passed through the staple to thereby lock the door in its closed position. To protect the operating parts of the lever etc., it may further be enclosed inside of an auxiliary cover 19. The cover 12 is arranged to be locked in place by means of a padlock 18a, and it will be apparent, therefore, that access to the lever L1 can only be had by authorized persons. For example, in actual practice, keys to the padlock 18a will be given only to signalmen, such as main-tainers, whereas keys to the lock 18 will be given both to signalmen and trainmen.

The apparatus also includes indication lamps HN and HR and a center tapped battery K.

As shown in the drawings, all parts are in their normal positions. That is to say, levers L and L1 both occupy their normal positions, switch E occupies its normal position, and section B-C is unoccupied by a train so that track relay D is energized. Under these conditions, magnet N is energized by virtue of a circuit passing from the left-hand half of the battery K through normal contact 8-8n of lever L, front contact 20 of relay D, normal contact 11-11n of auxiliary lever L1, the winding of magnet N, an asymmetric unit U1 in its low resistance direction, and common wire 21 back to battery K. Since magnet N is energized, fluid pressure is constantly admitted to motor M to hold the switch in its normal position. Furthermore, under these con-

ditions, an indication circuit is closed for the normal indication lamp HN passing from the right-hand half of battery K through common wire 21, an asymmetric unit U2 in its low resistance direction, normal contact 6-6a of circuit controller G, front contact 22 of relay D, normal contact 9-9n of lever L, and the filament of lamp HN back to battery K. Lamp HN is therefore energized to indicate that the switch and lever both occupy their normal positions and section B-C is unoccupied.

I shall now assume that the parts are in the positions in which they are shown in the drawings and that the towerman who has charge of lever L wishes to reverse switch E. To do this, he will move lever L from its normal position n to its reverse position r, thus opening contacts 8-8n and 9-9n and closing contacts 8-8r and 9-9r. The opening of contacts 8-8n and 9-9n interrupt, respectively, the previously traced circuit for the magnet N and for the indication lamp HN so that these parts now both become deenergized, while the closing of reverse contact 9-9r completes a circuit for the reverse magnet R passing from the left-hand half of battery K through contact 9-9r of lever L, front contact 22 of relay D, normal contact 10-10n of lever L1, the winding of magnet R, an asymmetric unit U3 in its low resistance direction, and line wire 21 back to battery K. Magnet R therefore becomes energized and causes the switch to move to its reverse position. This movement of the switch opens the normal contacts 6-6a and 7-7a of circuit controller G and closes the reverse contacts 6-6b and 7-7b, and when reverse contact 6-6b becomes closed, a circuit is completed for the reverse indication lamp HR passing from the right-hand half of battery K through common wire 21, asymmetric unit U2 in its low resistance direction, reverse contact 6-6b of circuit controller G, front contact 20 of track relay D, reverse contact 8-8r of lever L, and the filament of lamp HR to battery K. The completion of this circuit causes the reverse indication lamp to become lighted to indicate that the position of the switch and the position of lever L agree and that the auxiliary lever L1 occupies its normal position.

If, after the switch has been moved to its reverse position in the manner just described, the towerman desires to restore it to its normal position, he will restore lever L to its normal position. Under these conditions, as soon as the lever is moved away from its reverse position, the reverse indication circuit will become interrupted at contact 8-8r of lever L which will cause lamp HR to become extinguished, and the reverse control circuit will become interrupted at contact 9-9r of lever L which will cause the reverse magnet R to become deenergized; and when the lever reaches its normal position, the resultant closing of contact 8-8n of lever L will complete the previously described circuit for the normal magnet N. The normal magnet N will therefore become energized and will cause the switch to move to its normal position. When the switch reaches its full normal position, normal contact 6-6a of circuit controller G will become closed and will complete the previously traced indication circuit for the normal indication lamp HN. Lamp HN will then become lighted to indicate that the switch occupies its full normal position.

I shall now assume that the switch occupies its normal position and that a train enters the

track section B-C. The presence of the train in this track section will deenergize the track relay D, and this relay will therefore open its front contacts 20 and 22 and will close its back contact 23. The opening of front contacts 20 and 22 of relay D will interrupt all control circuits which were previously traced for the magnets N and R, thus preventing operation of the switch by means of the lever L as long as the train remains in section B-C. The opening of front contact 22 of relay D will also interrupt the normal indication circuit including lamp HN, thus causing this lamp to become extinguished. The closing of contact 23 of relay D will complete a locking circuit for the normal control magnet N passing from the left-hand half of battery K, through back contact 23 of relay D, normal contact 7-7a of circuit controller G, the winding of magnet N, asymmetric unit U1 in its low resistance direction, and common wire 21 back to battery K. This circuit will maintain magnet N energized under these conditions and will insure that the switch will remain in its normal position.

If a train enters section B-C when the switch occupies its reverse position, the operation of the apparatus will be similar to that just described when the switch occupies its normal position with the exception that under these latter conditions the opening of contacts 20 and 22 of track relay D will interrupt the reverse indication circuit for the reverse indication lamp HR and the normal energizing circuit for the reverse magnet R, while the closing of back contact 23 of relay D will complete an auxiliary energizing circuit for the reverse magnet R passing from the left-hand half of battery K through back contact 23 of relay D, reverse contact 7-7b of circuit controller G, the winding of magnet R, asymmetric unit U3 in the low resistance direction, and common wire 21 back to battery K.

I shall now assume that the parts are all in their normal positions in which they are shown in the drawings and that it is desired to control switch E locally by means of lever L1 to effect switching moves. To do this the trainman will first remove the padlock 18 and open the door 13, after which he will move lever L1 from its *n* to its *r* position. This movement of the lever will interrupt the normal control circuit for the normal magnet N at contact 11-11*n* of lever L1 and will complete at contact 10-10*r* an auxiliary control circuit for the reverse magnet R passing from the left-hand half of battery K through contact 8-8*n* of lever L, front contact 20 of relay D, reverse contact 10-10*r* of lever L1, the winding of magnet R, asymmetric unit U3 in its low resistance direction, and common wire 21 back to battery K. The energization of the reverse magnet R will cause the switch to move to its reverse position. This movement of the switch will operate the contacts of circuit controller D, and when the normal contact 6-6a becomes opened it will interrupt the circuit which was previously closed for the normal indication lamp HN so that this lamp will now become extinguished. All circuits for both indication lamps will then be opened, and these lamps will therefore now both remain dark to give an indication in the tower that the position of the switch is out of agreement with the position of the lever at the tower.

When the trainman desires to restore switch E to its normal position he will restore lever L1

to its normal position. This will open the auxiliary control circuit which was previously closed for the reverse magnet R, and will complete the normal control circuit for the normal magnet N, thereby moving the switch to its normal position. As soon as the switch reaches its normal position the resultant closing of contact 6-6a of circuit controller G will reestablish the circuit for the normal indication lamp HN and will thus indicate to the towerman that the switch is now in agreement with the position of the lever in the tower.

It should be particularly pointed out that since both the normal and reverse indication lamps become deenergized when the switch is operated by the local lever L1, if the trainman should fail to restore the local lever to its normal position after he has reversed the switch for any reason and this operation has been effected while the towerman is off duty, when the towerman returns to duty and finds that both the indication lamps are deenergized he will immediately be apprised that the position of the switch is out of agreement with the position of the lever in the tower and will accordingly send out a maintainer to locate the source of trouble.

I shall now assume that the switch E has been moved to its reverse position by operation of the lever L, and that it is desired to move it to its normal position locally to effect switching movements. To accomplish this latter result, the trainman will again move lever L1 to its reverse position. This movement will interrupt the circuit which was previously completed for the reverse magnet R and will complete a circuit for normal magnet N, which latter circuit may be traced from battery K through reverse contact 9-9*r* of lever L, front contact 22 of relay D, reverse contact 11-11*r* of auxiliary lever L1, the winding of normal magnet N, asymmetric unit U1 in its low resistance direction, and common wire 21 back to battery K. The normal magnet N will therefore become energized and will cause the switch to move to its normal position. As soon as the switch reaches its normal position, the resultant operation of the circuit controller G will interrupt the energizing circuit for the reverse indication lamp HR, and since all circuits for both indication lamps will then be open these lamps will both become dark to indicate that the position of the switch and the position of the lever in the tower are out of agreement.

If when the switch has been moved to its normal position by moving the auxiliary lever L1 to its reverse position it is desired to restore the switch to its reverse position this may be accomplished by restoring the lever L1 to its normal position. The operation under these conditions will be apparent from the foregoing description without further detailed description.

It will be observed that the scheme just described will allow a member of a train crew to reverse a switch without going to the tower, but it is necessary for the trainman to return the auxiliary lever to the normal position to restore the control by the lever in the tower to normal. If the auxiliary lever is left reversed, the switch may still be operated from the tower, but its position will be contrary to the lever position. The indication will not be received since the indication circuits remain normal and indicate correctly. Inasmuch as when the humping crew comes to work the towerman tries all switches for response by indications, an auxiliary lever

left reversed will be detected at once and can be corrected by members of the ground crew.

Referring now to Fig. 4, I have here shown a modified form of my invention in which, when the switch is reversed by the local control means and the car or train for which the switch is reversed passes over the switch, the switch will automatically assume a position in agreement with the position of the lever at the remote control point as soon as the train has cleared the track circuit in which the switch is located.

As here illustrated, the auxiliary manually operable lever L_1 utilized in Fig. 1 for effecting the local control of the switch has been replaced by a reversing relay F controlled by a push button P and the track relay D , and both the control and indication circuits have been modified somewhat in a manner which will be made clear presently. The push button P will preferably be housed at the switch in a manner similar to the lever L_1 in Figs. 1, 2 and 3, while the relay F will be housed at the same location as the track relay D . To prevent false indications, two additional asymmetric units U_4 and U_5 are provided. The apparatus not specifically mentioned is similar in all respects to that shown in Fig. 1.

As shown in Fig. 4, lever L and switch E both occupy their normal positions, sections $B-C$ is unoccupied so that track relay D is energized, push button P is open, and relay F is deenergized. Under these conditions, the reverse magnet R is deenergized, but the normal magnet N is energized over a normal control circuit passing from the left-hand half of battery K through normal contact $8-8n$ of lever L , wire 25 , back contact $26-26b$ of relay F , front contact 20 of track relay D , wire 27 , the winding of magnet N , asymmetric unit U_1 in its low resistance direction, and common wire 21 back to battery K . Furthermore, under the conditions described above, the reverse indication lamp is deenergized and the normal indication lamp is lighted to indicate that the position of the switch is in agreement with that of the lever. The circuit for the normal indication lamp may be traced from the right-hand half of battery K through common wire 21 , asymmetric unit U_2 in its low resistance direction, contact $6-6a$ of circuit controller D in its normal position, front contact 22 of track relay D , back contact $28-28b$ of reversing relay F , wire 29 , normal contact $9-9n$ of lever L , and the filament of lamp HN back to battery K .

I shall now assume that with the parts in the positions in which they are shown in Fig. 4, the towerman, wishing to reverse switch E , moves lever L from its normal position to its reverse position. Under these conditions, the opening of contact $9-9n$ of lever L will interrupt the normal indication circuit just described, while the resultant closing of contact $9-9r$ of lever L will complete a normal control circuit for the reverse magnet R passing from the left-hand half of battery K through contact $9-9r$ of lever L , wire 29 , back contact $28-28b$ of reversing relay F , front contact 22 of track relay D , wire 30 , the winding of reverse magnet R , asymmetric unit U_3 in its low resistance direction, and common wire 21 back to battery K . The reverse magnet R will therefore become deenergized and will cause the switch to be moved to its reverse position. When the switch reaches its reverse position, contact $6-6b$ of circuit control G will become closed and will com-

plete a reverse indication circuit. This reverse indication circuit may be traced from battery K through common wire 21 , asymmetric unit U_2 in its low resistance direction, contact $6-6b$ of circuit controller G , front contact 20 of track relay D , back contact $26-26b$ of reversing relay F , wire 25 , reverse contact $8-8r$ of lever L , and reverse indication lamp HR back to battery K . Lamp HR will therefore become lighted to indicate that the switch and lever both occupy their reverse positions.

If after the switch has been moved to its reverse position in the manner just described it is desired to restore it to its normal position from the remote point, the towerman will restore lever L to its normal position. This movement of the lever will interrupt the reverse indication circuit including lamp HR as well as the normal control circuit for the reverse magnet R , and will complete the previously described normal control circuit for the normal magnet N . The energization of the normal magnet will, of course, cause the switch to return to its normal position. When the switch reaches its normal position, contact $6-6a$ of circuit controller G will become closed in its normal position and will thereby complete the previously described normal indication circuit including the normal indication lamp HN . When this lamp becomes lighted, all parts will then be restored to the positions in which they are shown in the drawings.

I shall next assume that the parts are in the positions in which they are shown in the drawings and that it is desired to reverse the switch locally to effect switching moves. To do this, a member of the train crew will operate the push button P . The operation of this push button will complete a pick-up circuit for relay F passing from battery K through the winding of relay F , push button P , and common wire 21 back to battery K . Relay F will therefore pick up its armature and will thus open its back contacts $26-26b$ and $28-28b$ and close its front contacts $31, 26-26a$ and $28-28a$. The opening of back contact $26-26b$ of relay F will interrupt the normal control circuit for the normal magnet N so that this magnet will now become deenergized, while the opening of back contact $28-28b$ of relay F will interrupt the normal indication circuit to thereby cause the normal indication lamp HN to become extinguished. The closing of front contact 31 of reversing relay F will complete a stick circuit for this relay passing from battery K through the winding of relay F , front contact 23 of track relay D , front contact 31 of relay F and common wire 21 back to battery K . The completion of this stick circuit will cause relay F to remain energized until a car or train enters section $B-C$ and deenergizes track relay D even though push button P is immediately released, as will be obvious. The closing of front contact $28-28a$ of relay F will complete an auxiliary energizing circuit for the reverse magnet R passing from battery K through normal contact $8-8n$ of lever L , wire 25 , asymmetric unit U_4 in its low resistance direction, front contact $28-28a$ of relay F , front contact 22 of battery D , wire 30 , the magnet of relay R , asymmetric unit U_3 in its low resistance direction, and common wire 21 back to battery K . Reverse magnet R will therefore become energized and will cause the switch to move to its reverse position. When the switch reaches this latter position, contact $6-6b$ will become closed in its reverse po-

sition, and if asymmetric unit U5 were not provided a circuit would then be completed for the normal indication lamp HN passing from battery K through common wire 21, asymmetric unit U2 in its low resistance direction, contact 6-6b of circuit controller G, front contact 20 of relay D, front contact 26-26a of relay F, asymmetric unit U5, wire 29, normal contact 9-9n of lever L, and the filament of lamp HN back to battery K. However, the asymmetric unit U5 is so poled that the current is prevented from flowing in this circuit, and both indication lamps therefore remain deenergized to indicate a disagreement between the position of the switch and that of the lever.

If after the switch has been moved to its reverse position by virtue of the operation of the push button P in the manner just described the towerman moves lever L to its reverse position, the circuit over which the reverse magnet was previously energized will become interrupted at normal contact 8-8n of lever L, and an auxiliary energizing circuit for the normal magnet N will become completed at reverse contact 9-9r of lever L. This latter circuit may be traced from battery K through reverse contact 9-9r of lever L, wire 29, asymmetric unit U5 in its low resistance direction, front contact 26-26a of relay F, front contact 20 of relay D, the winding of magnet N, asymmetric unit U1 in its low resistance direction, and common wire 21 back to battery K. Magnet N will therefore become energized and will restore the switch to its normal position. When the switch reaches its normal position, the asymmetric unit U4 will act to prevent current from being supplied to lamp HR over a circuit which may be traced from battery K through common wire 21, asymmetric unit U2, contact 6-6a of circuit controller G, front contact 22 of relay HD, front contact 28-28a of relay F, asymmetric unit U4, wire 25, reverse contact 8-8r of lever L, and reverse indication lamp HR to battery K. As a result, both lamps HN and HR again remain deenergized to indicate the disagreement between the position of the switch and the lever.

I shall now assume that the switch has been moved to its reverse position by moving lever L to its reverse position and that under these conditions a trainman operates push button P to thereby energize relay F. The energization of relay F will of course cause it to pick up its armature and complete its stick circuit in the manner described hereinbefore. The energization of this relay will also interrupt the reverse indication circuit for lamp HR and the normal indication circuit for the reverse magnet R and will complete the auxiliary energizing circuit for magnet N described above when lever L is moved to its reverse position while relay F was picked up. The completion of this auxiliary energizing circuit for magnet N will cause the switch to return to its normal position. When the switch reaches this normal position, both indication lamps will remain deenergized for the reasons explained above.

I shall now assume that the switch has been moved from its normal to its reverse position by operation of push button P and that a train or car subsequently passes over this switch and into the siding J. As soon as the car or train enters section B-C, track relay D will become deenergized and will thereby open the circuit over which the reverse magnet R was previously

energized, and will complete the locking circuit for the reverse magnet R described in connection with Fig. 1 to thereby prevent the reversal of the switch under the train. The deenergization 5 of the track relay D will also interrupt the stick circuit for relay F so that this relay will immediately become deenergized. The deenergization of this relay under these conditions, however, will not have any effect on the remainder 10 of the apparatus until the car or train clears section B-C, whereupon the resultant picking up of relay D will complete the normal energizing circuit for the normal magnet N and will thus cause the switch to return to its normal position 15 since the lever L now occupies its normal position. When the switch reaches its normal position, the normal indication lamp HN will become lighted to indicate that the position of the switch is now in agreement with the position of the lever.

If a train traverses section B-C when the lever occupies its reverse position and the switch has been moved to its normal position by operation of push button P, the operation of the apparatus 25 will be similar to that just described with the exception that when the train vacates section B-C the switch will then return to its reverse position and will cause the reverse indication lamp HR to become lighted. It is thought that this latter operation will be apparent from an inspection of the drawings and from the foregoing description without further detailed description.

When relay F is deenergized and a train traverses section B-C, the resultant deenergization 35 of relay D will act to lock the switch in whichever extreme position it then occupies in a manner which it is thought will be readily apparent from an inspection of the drawings and from the foregoing description.

Referring now to Fig. 5, in the modified form 40 of my invention here illustrated, the apparatus is similar in all respects to that shown in Fig. 4 with the exception that relay F has been replaced by a two-winding relay F¹ which is controlled 45 jointly by lever L and by two push buttons P and P¹.

The relay F¹ will preferably be located in the same relay housing as relay D, and is provided with contacts which correspond exactly with the contacts of relay F and perform the same functions as the contacts of relay F.

The push button P is normally open, while the push button P¹ is normally closed. Both of these 50 push buttons will preferably be located in the housing of the switch machine in the manner similar to the auxiliary lever L¹ in Fig. 1.

The winding 32 of relay F¹ is provided with a pick-up circuit which passes from battery K through normal contact 8-8n of lever L, wire 55 25, asymmetric unit U4 in its low resistance direction, winding 32 of relay F¹, push button P, and common wire 21 back to battery K. This circuit will become closed if and only if push button P is operated while lever L occupies its normal position in which it is shown in the drawings, and the parts are so proportioned that when this circuit becomes closed relay F¹ will open its contacts 28-28b and 26-26b and will close 60 its front contacts 28-28a, 26-26a and 31.

Winding 32 of relay F¹ is also provided with a stick circuit which becomes closed when relay F¹ picks up by virtue of the pick-up circuit just traced for this winding. This stick circuit passes 65 from battery K through normal contact 8-8n of

lever L, wire 25, asymmetric unit U4 in its low resistance direction, winding 32 of relay F1, push button P1, front contact 31 of relay F1, and common wire 21 back to battery K. When this circuit is closed, relay F1 will remain energized even though the pick-up circuit which caused it to become energized is then opened.

Winding 33 of relay F1 is provided with a pick-up circuit which passes from battery K through reverse contact 9-9r of lever L, wire 29, asymmetric unit U5 in its low resistance direction, winding 33 of relay F1, push button P, and common wire 21 back to battery K. This latter pick-up circuit becomes closed when and only when push button P1 is operated while lever L occupies its reverse position, and the parts are so proportioned that when this latter circuit is closed relay F1 will attract its armature in the same manner as when the pick-up circuit for winding 32 becomes closed. It should be noted, however, that the winding 33 is connected in this circuit in such manner that the flux which is set up in the magnetic circuit of relay F1 by the current flowing in this winding will traverse the magnetic circuit in the opposite direction from that which is set up in the magnetic circuit by current supplied to winding 32 over its pick-up and stick circuits.

Winding 33 of relay F1 is also provided with a stick circuit which becomes closed when relay F1 picks up its armature due to the completion of the pick-up circuit for winding 33. This stick circuit may be traced from battery K through reverse contact 9-9r of lever L, wire 29, asymmetric unit U5 in its low resistance direction, winding 33 of relay F1, push button P1, front contact 31 of relay F1, and common wire 21 back to battery K, and this circuit is effective to retain relay F1 energized after it has become energized by virtue of the pick-up circuit for winding 33 until either push button P1 is operated or lever L is moved away from its reverse position. It will be apparent that the current which flows in winding 33 when it is energized by virtue of its stick circuit traverses the winding in the same direction as that supplied to the winding when it is energized by virtue of its pick-up circuit.

With the apparatus constructed as shown in Fig. 5, when relay F1 is deenergized, as will normally be the case, operation of the lever L will cause the switch to reverse in exactly the same manner as was described in connection with Fig. 4 when relay F was deenergized, the only difference being that each of the circuits which are completed will include a contact of relay F1 instead of a corresponding contact of relay F, it being understood that both relays have equivalent contacts.

If it is desired to reverse switch E locally to effect switching movements while the towerman is off duty, one of the trainmen will operate push button P. This will complete either the pick-up circuit for winding 32 of relay F1, or the pick-up circuit for winding 33, depending upon whether lever L then occupies its normal or its reverse position, and will thus cause relay F1 to pick up its armature and complete the stick circuit for the winding whose energization caused the armature to pick up. The energization of relay F1 will, of course, cause the switch to reverse in the same manner as when relay F in Fig. 4 became energized and will cause both the indication lamps to become deenergized to indicate that the position of the switch is out of agreement

with that of the lever. Since this operation is similar to that described hereinbefore in connection with Fig. 4, it is believed to be unnecessary to describe it in detail herein.

- 5 If, after a trainman has reversed the switch in the manner just described, he desires to restore it to its original position, he may accomplish this result by operating push button P1. This will interrupt the stick circuit over which relay F1 is then energized, and will thus cause this relay to again become deenergized since all of the other circuits for relay F1 will then be open. As soon as relay F1 becomes deenergized, the switch will return to the position corresponding to that of the lever, and when it reaches this position, the corresponding indication lamp will become lighted.

I shall now assume that a trainman who has reversed the switch locally by operating push button P fails to restore it to its original position, and that when the towerman comes on duty he desires to regain normal control of the switch. To do this, he will reverse lever L. The reversal of the lever under these conditions will interrupt the stick circuit for whichever winding of the relay was previously energized, and if the lever is operated sufficiently rapidly so that it reaches its opposite extreme position before front contact 31 of relay F1 has had an opportunity

20 to open, the stick circuit for the other winding of the relay will become completed. For example, I shall assume that relay F1 is energized by virtue of the stick circuit for winding 32, and that lever L is moved rapidly from its normal to its reverse

25 position. This operation of the lever will interrupt at its normal contact 8-8n the stick circuit for winding 32 of relay F1, and will complete at its reverse contact 9-9r the stick circuit for winding 33. The interruption of the stick circuit

30 of the relay will of course deenergize this winding, while the completion of the stick circuit for winding 33 will energize this winding. The energization of winding 33 will set up a flux in the magnetic circuit of relay F1 which bucks

35 that due to the decaying flux of winding 32, and as a result, the two fluxes set up in the magnetic circuit of relay F1 will pass through zero and will thus cause the armature of relay F1 to release. When this happens, the stick circuit for

40 winding 33 will become interrupted, and both windings of relay F1 will then become deenergized and will subsequently remain deenergized. As soon as relay F1 releases its armature, if section B-C is then unoccupied so that track relay

45 D is energized, the normal energizing circuit for the reverse magnet R will become completed, as well as the normal indication circuit for the reverse indication lamp HR. The reverse indication lamp will therefore become lighted, which will

50 inform the towerman that the position of the switch now agrees with that of the lever. If the towerman then desires to restore the switch to its normal position, he may do so by returning lever L to its normal position in the usual manner.

55 If the towerman had moved lever L to its reverse position under the conditions above described sufficiently slowly to permit front contact 31 of relay F1 to open before reverse contact 9-9r of this lever became closed, then winding 33 of relay F1 would not have become energized.

60 The operation of the apparatus as a whole would otherwise have been the same as described above. If the lever had been in its reverse position when the towerman came on duty under the

75 conditions described above and he had moved

the lever rapidly to its normal position, the operation of the lever would have deenergized winding 33 and would have caused winding 32 to become momentarily energized by virtue of its stick circuit to thereby set up in the magnetic circuit of relay F1 opposing fluxes which would cause the armature to release. As soon as relay F1 had released its armature the control of the switch would have been restored to the towerman in a manner which will be readily understood from an inspection of the drawing and from the foregoing description without further detailed description.

One advantage of the apparatus constructed in the manner shown in Fig. 5 is that it enables the towerman to restore the switch to its original position at all times after it has been reversed by the trainman.

Another advantage of the apparatus constructed as shown in Fig. 5 is that if a trainman fails to restore the switch to the position in which it agrees with that of the lever in the tower after he has reversed the switch, the towerman may readily gain normal control of the switch without the necessity for sending a maintainer out to the switch or causing a train to pass through the switch as will be readily understood.

Although I have herein shown and described only a few forms of railway switch operating apparatus embodying my invention, it is understood that various changes and modifications may be made therein within the scope of the appended claims without departing from the spirit and scope of my invention.

Having thus described my invention, what I claim is:

1. In combination, a railway track switch, a normal and a reverse control magnet for controlling movements of said switch to normal and reverse positions respectively, a control lever located at a point remote from said switch and having normal and reverse positions, local control means having first and second positions, means effective when said local control means occupies its first position for energizing said normal magnet or said reverse magnet according as said lever occupies its normal or its reverse position, and other means effective when said local control means occupies its second position for energizing said reverse magnet or said normal magnet according as said lever occupies its normal or its reverse position.

2. In combination, a railway track switch, a normal and a reverse control magnet for controlling movements of said switch to normal and reverse positions respectively, a control lever located at a point remote from said switch and movable to normal and reverse positions, local control means having two positions, means for energizing said normal magnet when said lever occupies its normal position and said remote control means occupies its one position or when said lever occupies its reverse position and said local control means occupies its other position, and means for energizing said reverse magnet when said lever occupies its reverse position and said local control means occupies its one position or when said lever occupies its normal position and said local control means occupies its other position.

3. In combination, a railway track switch, a normal and a reverse control magnet for controlling movements of said switch to normal and reverse positions respectively, a control lever located at a point remote from said switch and

having normal and reverse positions, local control means having first and second positions, means effective when said local control means occupies its first position for energizing said normal magnet or said reverse magnet according as said lever occupies its normal or its reverse position, other means effective when said local control means occupies its reverse position for energizing said reverse magnet or said normal magnet according as said lever occupies its normal or its reverse position, a circuit controller controlled in accordance with the position of said switch, and indication means controlled by said circuit controller and said lever and effective to indicate when said switch and said lever occupy corresponding positions.

4. In combination, a railway switch having normal and reverse positions, a switch operating mechanism operatively connected with said switch and provided with a normal and a reverse magnet and effective for moving said switch to its normal or its reverse position according as said normal or said reverse magnet is energized, a circuit controller operated by said switch and including a normal contact which is closed only when said switch occupies its normal position and a reverse contact which is closed only when said switch occupies its reverse position, a manually operable lever located at a point remote from said switch movable between normal and reverse positions and including normal and reverse contacts which are closed according as said lever occupies its normal or its reverse position, a normal energizing circuit for said normal magnet including a first normal contact of said lever, a normal energizing circuit for said reverse magnet including a first reverse contact of said lever, a normal and a reverse indication means, an energizing circuit for said normal indication means including a second normal contact of said lever and a normal contact of said circuit controller, and an energizing circuit for said reverse indication means including a second reverse contact of said lever and a reverse contact of said circuit controller, the combination with the aforementioned instrumentalities of local control means having two positions and four contacts two closed in each position, the one contact which is closed is the one position being included in the normal energizing circuit for said normal magnet and the other contact which is closed in the normal position of said local control means being included in the normal energizing circuit for said reverse magnet, an auxiliary energizing circuit for said normal magnet including said first normal contact of said lever and a contact of said local control means closed in its other position, and an auxiliary energizing circuit for said reverse magnet including said first reverse contact of said lever and a contact of said local control means closed in its other position.

5. In combination; a railway track switch, a normal and a reverse control magnet for controlling movements of said switch to normal and reverse positions, respectively, a control lever located at a point remote from said switch and movable to normal and reverse positions, a reversing relay, a push button located adjacent said switch, means controlled by said push button for energizing said reversing relay, circuit means effective when said reversing relay is deenergized for energizing said normal or said reverse magnet according as said lever occupies its normal or its reverse position, and other circuit means effective when said reversing relay is energized

for energizing said reverse or said normal magnet according as said lever occupies its normal or its reverse position.

6. In combination; a railway track switch, a normal and a reverse control magnet for controlling movements of said switch to normal and reverse positions, respectively, a control lever located at a point remote from said switch and movable to normal and reverse positions, a reversing relay, a push button located adjacent said switch, means controlled by said push button for energizing said reversing relay, circuit means effective when said reversing relay is deenergized for energizing said normal or said reverse magnet according as said lever occupies its normal or its reverse position, other circuit means effective when said reversing relay is energized for energizing said reverse or said normal magnet according as said lever occupies its normal or its reverse position, and means effective when said reversing relay becomes energized for maintaining it energized until a train enters a track section in which said switch is located.

7. In combination; a railway track switch, a normal and a reverse control magnet for controlling movements of said switch to normal and reverse positions, respectively, a control lever located at a point remote from said switch and movable to normal and reverse positions, a reversing relay, a push button located adjacent said switch, means controlled by said push button for energizing said reversing relay, circuit means effective when said reversing relay is deenergized for energizing said normal or said reverse magnet according as said lever occupies its normal or its reverse position, other circuit means effective when said reversing relay is energized for energizing said reverse or said normal magnet according as said lever occupies its normal or its reverse position, indication means associated with said lever, circuit means for energizing said indication means to indicate when said switch and said lever occupy corresponding positions, said last mentioned circuit means being in part common with the circuit means for energizing said control magnets, and asymmetric units effective to render said circuit means ineffective to control said indication means when said reversing relay is picked up unless said switch and said lever then occupy corresponding relative positions.

8. In combination, a railway track switch, a normal and a reverse control magnet for controlling movements of said switch to normal and reverse positions respectively, a control lever located at a point remote from said switch and movable to normal and reverse positions, a reversing relay, means disposed adjacent said switch for controlling said reversing relay, means effective when said reversing relay is deenergized for energizing said normal or said reverse magnet according as said lever occupies its normal or its reverse position, and other circuit means effective when said reversing relay is energized for energizing said reverse or said normal magnet according as said lever occupies its normal or its reverse position.

9. In combination, a section of railway track including a track switch, a track circuit for said section including a track relay, a control lever located at a point remote from said switch and movable to normal and reverse positions, a reversing relay, a manually operable contact located adjacent said switch, means controlled by said contact for energizing said reversing relay,

means effective when said reversing relay becomes energized for maintaining it energized until said track relay subsequently becomes deenergized, circuit means effective when said reversing relay is deenergized for energizing said normal or said reverse magnet according as said lever occupies its normal or its reverse position, and other circuit means effective when said reversing relay is energized for energizing said reverse or said normal magnet according as said lever occupies its normal or its reverse position.

10. In combination, a section of railway track including a track switch, a track circuit for said section including a track relay, a control lever located at a point remote from said switch and movable to normal and reverse positions, a reversing relay, a manually operable contact located adjacent said switch, means controlled by said contact for energizing said reversing relay, means effective when said reversing relay becomes energized for maintaining it energized until said track relay subsequently becomes deenergized, circuit means effective when said reversing relay is deenergized for energizing said normal or said reverse magnet according as said lever occupies its normal or its reverse position, other circuit means effective when said reversing relay is energized for energizing said reverse or said normal magnet according as said lever occupies its normal or its reverse position, indication means associated with said lever, circuit means for energizing said indication means to indicate when said switch and said lever occupy corresponding positions, said last mentioned circuit means being in part common with the circuit means for energizing said control magnets, and asymmetric units effective to render said circuit means ineffective to control said indication means when said reversing relay is picked up unless said switch and said lever then occupy corresponding relative positions.

11. In combination, a railway track switch, a normal and a reverse magnet for controlling movements of said switch to normal and reverse positions respectively, a control lever located at a point remote from said switch and comprising normal and reverse contacts, a two-winding reversing relay, a manually operable normally open contact located adjacent said switch, a manually operable normally closed contact located adjacent said switch, a pick-up circuit for the one winding of said relay including a first normal contact of said lever and said manually operable normally open contact, a stick circuit for said one winding of said reversing relay including said first normal contact and a front contact of said relay and said manually operable normally closed contact, a pick-up circuit for the other winding of said relay including a first reverse contact of said lever and said manually operable normally open contact, a stick circuit for said other winding of said reversing relay including said first reverse contact and said front contact of said reversing relay and said manually operable normally closed contact, said two windings being connected in said stick circuits in such manner that the fluxes set up in the magnetic circuit of said relay when said stick circuits are energized will traverse the magnetic circuit in opposite directions, and means controlled jointly by said lever and said reversing relay for selectively energizing said normal and said reverse magnets.

12. In combination, a railway track switch, a normal and a reverse magnet for controlling movements of said switch to normal and reverse

positions respectively, a control lever located at a point remote from said switch and comprising normal and reverse contacts, a two-winding reversing relay, a manually operable normally open contact located adjacent said switch, a manually operable normally closed contact located adjacent said switch, a pick-up circuit for the one winding of said relay including a first normal contact of said lever and said manually operable normally open contact, a stick circuit for said one winding of said reversing relay including said first normal contact and a front contact of said relay and said manually operable normally closed contact, a pick-up circuit for the other winding of said relay including a first reverse contact of said lever and said manually operable normally open contact, a stick circuit for said other wind-

ing of said reversing relay including said first reverse contact and said front contact of said reversing relay and said manually operable normally closed contact, said two windings being connected in said stick circuits in such manner that the fluxes set up in the magnetic circuit of said relay when said stick circuits are energized will traverse the magnetic circuit in opposite directions, circuit means effective when said reversing relay is deenergized for energizing said normal or said reverse magnet according as said lever occupies its normal or its reverse position, and other circuit means effective when said reversing relay is energized for energizing said reverse or said normal magnet according as said lever occupies its normal or its reverse position.

JOHN W. LOGAN, JR.
